UNITED STATES PATENT OFFICE.

WALTER R. MONTGOMERY, OF SHREVEPORT, LOUISIANA.

FOLDING TABLE.

SPECIFICATION forming part of Letters Patent No. 757,481, dated April 19, 1904.

Application filed November 28, 1902. Serial No. 133,126. (No model.)

To all whom it may concern:

Be it known that I, WALTER R. MONTGOMERY, a citizen of the United States, residing at Shreveport, in the parish of Caddo and State of Louisiana, have invented a new and useful Folding Table, of which the following is a specification.

The invention relates to improvements in folding tables.

10 The object of the present invention is to improve the construction of folding tables and to provide an exceedingly simple and inexpensive one having a drawer and provided with legs adapted to fold against the top of the table without necessitating the removal of the drawer.

15 A further object of the invention is to provide a construction which will enable the legs at either end of the table to fold directly against the top and which will permit the other set of legs to fold compactly against the legs which are arranged against the top.

Another object of the invention is to dispense with hinges and to facilitate assembling 20 the parts and connecting the folding legs to the top of the table.

25 The invention consists in the construction and novel combination and arrangement of parts hereinafter fully described, illustrated in the accompanying drawings, and pointed out in the claims hereto appended.

30 In the drawings, Figure 1 is a plan view, partly in section, of a folding table constructed in accordance with this invention, the table being folded. Fig. 2 is a longitudinal sectional view of the same, the parts being arranged for use. Fig. 3 is a transverse sectional view. Fig. 4 is a detail perspective view of one corner of the table. Fig. 5 is a 35 detail view of a portion of one leg and the connecting-bar. Fig. 6 is a detail sectional view of a portion of a table, illustrating a portion of the legs.

Like numerals of reference designate corresponding parts in all the figures of the drawings.

45 Fig. 1 designates the top of a table provided with side and end rails 2 and 3, the end rails 3 being permanently secured or otherwise suitably fixed to the lower face of the top 1 and

provided at their ends with bearings for the reception of journals 2^a of the side rails, which are adapted to swing transversely of the table, as hereinafter explained.

The side rails 2 are provided near their ends 55 with bearing slots or recesses 4, which are elongated to permit the legs 5 of the table to be moved to and from the top 1 in folding the legs, whereby either set of legs may be arranged against the top and the other set compactly folded against the set which is next to the top. The legs 5 of each end are connected by a transverse bar 6, which is provided at its ends with journals 7, arranged in the bearing slots or recesses 4, and the latter are 60 vertically disposed, as clearly shown in Fig. 6, and the journals may be readily introduced into the slot or bearing recesses when the side rails are swung outward. The side rails are normally held in the position illustrated in the 65 accompanying drawings by means of transverse springs 8, connected with the side rails and with the bars 6 and constructed and arranged substantially as shown and described in Patent No. 665,325, dated January 1, 1901. 70 The springs are adapted to swing the legs outward in unfolding the table, and they are capable of securely holding the side rails in proper position and of preventing the same from accidentally swinging outward and releasing the legs. Either set of legs is adapted 75 to be folded flat against the lower face of the top of the table, and the other set of legs may be compactly folded against the first set, as the journals will move outward in the bearing slots or recesses of the side rails. The legs are held rigidly with the sides and top when the table is in use by means of catches 80 85 9 and 10, consisting of resilient plates secured at their inner ends to the inner faces of the 90 side rails at the recesses 11 thereof and having their outer portions bent at right angles to form arms 12 and to provide shoulders 13 for engaging the inner side faces of the legs. The shoulders are arranged vertically and lock 95 the legs against inward movement to prevent them from folding. The engaging portions of the catches are also provided with horizontal flanges or lugs 14, which fit in kerfs or recesses 15 of the legs, whereby the journals 100

are locked in the upper portion of the bearing-slots of the side rails. The arms 12 of the catches extend through slots 16 of the side rails and terminate in suitable grips or handles which enable the shoulders and the lugs or flanges to be readily withdrawn from engagement with the legs to permit the latter to fold; but the handle portions of the catches may be constructed in any other suitable manner. The kerfs or recesses 15, which receive the lugs or flanges, extend horizontally from the outer side edges of the upper portions of the lugs or legs to permit the lugs or flanges to slide readily into and out of engagement with them, and the shanks or body portions of the resilient plates are arranged at a slight angle to the inner faces of the side rails and are adapted to throw the shoulders and the flanges automatically into engagement with the legs when the latter are brought from their folded position to their operative position.

The table is held in its folded position by means of resilient outwardly-extending arms 17, arranged at an angle to the inner faces of the side rails and mounted on one of the catches of each side of the table. The arms engage the outer set of legs, as clearly shown in Fig. 1, and are adapted to be readily pressed back against the inner faces of the side rails when it is desired to arrange the legs for use. The resilient arms 17 are adapted to engage either set of legs, and, if desired, each of the catches may be provided with one of the said arms; but one at each side of the table will be sufficient.

The table is provided at the lower face of its top with centrally-arranged ways 18, terminating short of the side rails and receiving a drawer 19, provided at opposite sides with suitable grooves to be engaged by the ways. The ways preferably consist of suitable cleats provided with flanges extending into the grooves of the drawer, and the latter is adapted to be arranged in the center of the table between the legs when the latter is folded, whereby the drawer is permitted to remain on the table when the latter is folded. One of the side rails is provided with an opening 20, through which the drawer may be drawn, and the outward movement of the drawer is limited by suitable stops 21, mounted on the drawer at the lower face thereof and arranged to engage one of the side rails when the drawer is pulled out. When the table is in position for use, the inward movement of the drawer is limited by a pivoted button secured to the lower face of the table-top, and this button 22 is adapted to be arranged transversely of a notch or recess 23 of the back of the drawer to pass through the said notch or recess when it is desired to arrange the drawer at the middle of the table preparatory to folding the legs. The drawer when arranged at the center of the table terminates short of and is

spaced from the side rails to provide spaces for the legs, and the latter will prevent the drawer from leaving the ways. The pivoted button 22 is also adapted to turn longitudinally of the table, as indicated in dotted lines 70 in Fig. 2, to provide a stop for limiting the inward movement of the drawer.

It will be seen that the folding table is exceedingly simple and inexpensive in construction, that it is adapted when not in use to be 75 compactly folded, and that when folded the drawer does not have to be removed. Furthermore, it is clear that hinges are dispensed with and that the hinged legs are readily connected with pivotally mounted or hinged sides 80 which are journaled in the fixed end rails.

It will be understood that various changes in the form, proportion, and minor details of construction within the scope of the appended claims may be resorted to without departing 85 from the spirit or sacrificing any of the advantages of the invention.

What I claim is—

1. A table having a top provided with ways terminating short of the edges of the table, a 90 drawer arranged in the said ways and adapted to be moved in the center of the table and provided at its inner end with a notch, a movable stop mounted on the top and arranged to limit the inward movement of the drawer and adapted also to be arranged to pass through the notch or recess, and folding legs arranged to fold at opposite sides of the drawer when the latter are at the center of the table, substantially as described. 95

2. In a folding table, the combination of a top, a folding leg pivotally connected with the top and capable of a limited sliding movement and a catch mounted on the top of the table and arranged to engage the leg to hold it from 100 swinging, said catch being also provided with a lug or flange to lock the leg against sliding, substantially as described.

3. In a folding table, the combination of a top having side rails provided with elongated 110 bearings, folding legs provided with kerfs or recesses and having journals arranged in the bearings, and catches mounted on the side rails and provided with shoulders for engaging the side faces of the legs and having lugs 115 or flanges for engaging the kerfs or recesses, substantially as described.

4. In a folding table, the combination of a top provided with side and end rails, the side rails having elongated bearing recesses or 120 slots, folding legs arranged in pairs and having journals fitting in the bearing recesses or slots, and catches mounted on the side rails and engaging the legs to hold the same in their operative position and provided with arms for locking the same in their folded position, substantially as described. 125

5. In a folding table, the combination of a top provided with side and end rails, the side rails being pivotally mounted and provided 130

with bearings, and legs having pivots arranged in the bearings of the side rails, substantially as described.

6. In a folding table, the combination of a top, end rails secured to the top and provided with bearings, side rails provided with pivots or journals arranged in the bearings in the end rails and adapted to swing outward, said side rails also being provided with bearings, and folding legs provided with pivots or journals arranged in the bearings of the side rails and adapted to be placed therein and removed therefrom, when the side rails are swung outward, substantially as described.
- 15 7. In a folding table, the combination of a top, fixed end rails secured to the top and provided with bearings, side rails having journals arranged within the bearings, said side rails being also provided with bearings and adapted 20 to swing inward and outward, legs arranged in pairs and provided with journals arranged in the bearings of the side rails and locking devices mounted on the side rails and carried

by the same and adapted to engage the legs to hold the latter in their operative position, substantially as described.

8. In a folding table, the combination of a top provided with bearings, side rails having pivots or journals arranged in the bearings and adapted to swing outward, said side rails also being provided with bearings, legs arranged in pairs and having pivots fitting in the bearings of the side rails, and catches mounted on the side rails and engaging the legs, said legs being adapted to be interlocked with and removed from the side rails when the latter are swung outward, substantially as described.

In testimony that I claim the foregoing as my own I have hereto affixed my signature in the presence of two witnesses.

WALTER R. MONTGOMERY.
